UNITED STATES PATENT OFFICE.

AUGUST BALDASSINI, OF CUPERTINO, CALIFORNIA.

APPARATUS FOR OILING WINDMILLS.

No. 845,676.

Specification of Letters Patent.

Patented Feb. 26, 1907.

Application filed November 9, 1904. Serial No. 232,026.

To all whom it may concern:

Be it known that I, AUGUST BALDASSINI, a citizen of the United States, residing at Cupertino, in the county of Santa Clara and State of California, have invented new and useful Improvements in Apparatus for Oiling Windmills, of which the following is a specification.

The object of my invention is to provide a simple and efficient apparatus with which to equip windmills, so that the bearings thereof can be fed with a lubricant from a supply-receptacle located at the top of the mill and the said lubricant be supplied to said receptacle by manipulations entirely from below, thereby obviating the necessity of climbing the mill and the hazard attending the usual methods of oiling, and also permitting a lighter and less expensive construction of mill.

The invention consists in an oil-feeding receptacle having ducts leading to the bearings of the mill and carried by the rotary top support thereof, guides or tracks extending from or near the ground into proximity to the top support, a carrier for said guides or tracks carrying an oil-receptacle and adapted to extend to the oil-feeding receptacle, and means for hoisting said carrier and for causing the contents of its receptacle to be discharged into the other receptacle.

The invention further consists in certain novel features in the construction and arrangement of parts, all as hereinafter described, and specifically set forth in the appended claims.

In the accompanying drawings, Figure 1 is a view in elevation of the top portion of a windmill, showing the application of the invention; Fig. 2, a side elevation of a similar portion, showing the derrick or stationary structure by section taken on the line *x* *x* of Fig. 1; Fig. 3, an enlarged side view of a portion of the carrier and its operating parts and showing in dotted lines the position of the oil-receptacle and its operating means when discharging; Fig. 4, a view in elevation, showing the inner side of a portion of the carrier; and Fig. 5, a section view taken 50 through the oil-feeding receptacle.

Referring to the drawings, 1 indicates the stationary structure or derrick of the mill, and 2 the rotary structure at the top thereof for the shaft 3 from the wind-wheel. (Not shown.) Only so much of the shaft 3 is shown in the drawings to show its bearings

4 and 5. Rigid tubes 6 and 7, having communication with the interior of these bearings, respectively, extend from the top thereof and form supports for the receptacle 8, which 60 is adapted to contain the supply of oil to be fed to the bearings through said tubes. This receptacle occupies a central position, so that the rotation of the top structure 2 will not disturb its proper relation to the 65 other elements of the apparatus. This receptacle is provided with a circular cover 9 of such size as to provide an annular overhanging portion to be engaged by the oil-supply carrier 10 to lift the cover when supplying the receptacle 8 with oil. A vertical pin or guide 11, rigidly affixed to the center of the receptacle 8, extends through the opening 12 in said cover and serves to retain the cover, while permitting it to be raised by 70 contact with the carrier 10 at any point of its circumference. Further protection is given the lubricant by arranging a screen 13 within the receptacle 8 and sufficiently below the top thereof as not to interfere with 75 the working of the apparatus by which the receptacle is supplied with oil.

Extending from the top of the stationary structure to a point at the base thereof are stretched two parallel wires 14 to form a 80 track or way for the carrier 10, which is preferably a wooden bar slidably secured thereon by metal loops or guides 15, located adjacent the lower end of said carrier. The location and direction of the track and the length of the 85 carrier is such as to bring the upper end of the carrier in close proximity to the receptacle 8 when said carrier has reached the upper terminus of the track.

The oil-supplying receptacle 16 is tiltably 90 supported at the upper end of the carrier between the arms 17, projecting therefrom and in which the journals 18 have their bearings. These arms 17 project above the top of this receptacle in order that the cover 9 of the oil-feeding receptacle 8 may be raised in advance of the arrival of the supply-receptacle 16 at the limit of its upward movement, and the said cover be supported on said arms and out of the way during the operation of tilting the 100 supply-receptacle.

The carrier 10 is raised and lowered from the ground by means of a cord 19 or other equivalent means attached to the carrier below the projecting part thereof and passing 110 over a pulley or guide 20, mounted in the stationary structure 1 at the terminus of the

track 14. The lowering of the carrier may be accomplished by gravity and controlled by gradually paying out the hoisting-cord 19; but, if desired, a pull-cord can be attached to 5 the carrier for the purpose of accomplishing its descent in a more positive manner.

In order to accomplish the tilting of the receptacle 16 upon its arrival at its proper position with reference to the receptacle 8 and 10 as a result of the hoisting operation, there is attached to the receptacle 16, by means of the eye 21, located above the pivotal point of said receptacle, a cord 22, which connects with the hoisting-cord 19 at a point 23. Normally 15 this cord 22 is inactive and remains slack and is not effected by the pull on the cord 19 as long as the lower end of said cord 22 remains on the carrier side of the pulley or guide 20; but when the carrier has reached a point to 20 bring the lower end of cord 22 over the pulley, as shown in Fig. 3, the continued hoisting operation of cord 19 carries the lower end of 25 said cord 22 downward, eliminating the slack therefrom and causing the tilting of the receptacle 16 to take place, as shown by dotted lines in Fig. 3. Upon any release of the hoisting-cord 19 the receptacle 16 is free to right itself by gravity.

In order to maintain the receptacle 16 in 30 its vertical position and prevent any swinging movement thereof until tilted as above, the carrier is provided with a sliding bolt 24, held in position by guides 25 and adapted to engage a keeper 26, with which the receptacle 35 16 is provided, and is normally projected by means of the springs 27. This bolt is automatically retracted from its keeper 26 by the action of the tilting-cord 22 in advance of the tilting action of the receptacle, as this cord 40 passes through a guide 28 on said bolt and is provided with a stop 29, which engages said 45 guide and causes the retraction of the bolt, and by slack being provided in said cord between the said stop and the eye 21 the retraction is accomplished before the 50 cord is tensioned to tilt the receptacle 16, which follows upon the continued retraction of the bolt. The slack referred to also permits the receptacle 16 to return by gravity to 55 its normal position in advance of the bolt, which is also controlled by the stop 29 on its return and allowed to reach its full projection to engage its keeper 26 only after the receptacle 16 has reached its normal position.

55 Having thus fully described the invention, what I claim is—

1. In a windmill, the combination with the tower and the mill rotatably mounted thereon, of a carrier mounted to travel on said 60 tower and adapted to project above the same when carried to the top thereof, an oil-feeding receptacle carried by the mill, an oil-receptacle for the projecting end of said carrier, and means for causing the oil-receptacle 65 of the carrier to empty into said oil-feeding

receptacle, substantially as and for the purpose set forth.

2. In a windmill, the combination with the tower and the mill rotatably mounted thereon, of a track or way extending up said tower and 70 terminating at the top thereof, an oil-feeding receptacle carried by the mill, a carrier adapted to travel on said track or way and adapted to project above the tower on reaching the upper terminus of said track or way, an oil-receptacle for the projecting end of said carrier and means for causing the same to empty into the oil-feeding receptacle, substantially as and for the purpose set forth. 75

3. In a windmill, the combination with the 80 tower and the mill rotatably mounted thereon, of a carrier mounted to travel to the top of said tower and to project above the same on reaching the top thereof, an oil-feeding receptacle carried by the mill, an oil-receptacle 85 tiltably mounted on the projecting end of said carrier, and means for tilting the carrier-receptacle to empty it into the oil-feeding receptacle substantially as and for the purpose set forth. 90

4. In a windmill, the combination with the tower and the mill rotatably mounted thereon, of a carrier mounted to travel to the top of said tower and adapted to project above the same on reaching the top thereof, an oil-feeding receptacle carried by the mill, an oil-receptacle 95 tiltably mounted on the projecting end of said carrier and adapted when tilted in its projected position to empty into said oil-feeding receptacle, a hoisting-cable 100 for said carrier running to the top of said tower and downward therefrom, and means connected to said hoisting means for tilting the oil-receptacle of the carrier by the hoisting operation, substantially as and for the purpose set forth. 105

5. In a windmill, an oil-feeding receptacle carried by the rotary top structure, a track or way extending up the stationary structure, a carrier for said track or way, an oil-receptacle 110 tiltably on said carrier and adapted to be projected to said oil-feeding receptacle, a hoisting means connected to the carrier and passing over and downward from a guide at the upper terminus of the track or way, a locking-bolt for said tilttable oil-receptacle, and means connecting said bolt with the hoisting means, and adapted to be drawn downward thereby at a predetermined point in the hoisting operation, substantially as and for the purpose set forth. 115

6. In a windmill, an oil-receptacle carried by the rotary top structure, a track or way extending up the stationary structure, a carrier for said track or way, an oil-receptacle 120 tiltably on said carrier and adapted to be projected to said oil-feeding receptacle, a hoisting means connected to the carrier and passing over and downward from a guide at the upper terminus of said track or way, and a 125

normally slack connection between said tilt-
able receptacle and the hoisting means,
adapted to receive a pulling strain to tilt said
receptacle, substantially as and for the pur-
pose set forth.

7. In a windmill, an oil-receptacle carried
by the rotary top structure, a track or way
extending up the stationary structure, a car-
rier for said track or way, an oil-receptacle
tiltable on said carrier, and having a bolt for
locking said receptacle against tilting, hoist-
ing means connected to the carrier, and pass-
ing over and downward from a guide or pul-
ley at the upper terminus of the track or way,
substantially as and for the purpose set forth.
8. In a windmill, an oil-feeding receptacle
carried by the rotary top structure, a cover
for said receptacle, a carrier movable on the
stationary structure, an oil-receptacle adapt-
ed to be projected by said carrier to the oil-
feeding receptacle and to engage said cover,
means for raising said carrier, and means for

causing the carrier-receptacle to empty into
the oil-feeding receptacle, substantially as
and for the purpose set forth.

9. In a windmill, an oil-feeding receptacle
carried by the rotary top structure, a cover
for said receptacle, a central guide for said
cover extending from said receptacle, a car-
rier, an oil-receptacle, adapted to be project-
ed from the stationary structure to the oil-
feeding receptacle, and to engage and raise
said cover, means for raising said carrier, and
means for causing the carrier-receptacle to
empty into the oil-feeding receptacle, substan- 35
tially as and for the purpose set forth.

In testimony whereof I have signed my
name to this specification in the presence of
two subscribing witnesses.

AUGUST BALDASSINI.
